CLAIM

The ornamental design for a one piece nursing arm pillow, as shown and described.

DESCRIPTION

FIG. 1 is a front side perspective view of the one piece nursing arm pillow;

FIG. 2 is a front side view of the one piece nursing arm pillow;

FIG. 3 is a back side view of the one piece nursing arm pillow;

FIG. 4 is a right side view of the one piece nursing arm pillow;

FIG. 5 is a left side view of the one piece nursing arm pillow; FIG. 6 is a top side view of the one piece nursing arm pillow; and,

FIG. 7 is a bottom side view of the one piece nursing arm pillow.

Stitching lines, and shading in the drawings are for layout purposes only, none of which are part of the claimed design.

1 Claim, 7 Drawing Sheets
